ROSARY

Anna C. Ratajack, Calumet City, Ill.

Application January 27, 1959, Serial No. 54,349

Term of patent 7 years

(Cl. D45—16)

Fig. 1 is a plan view of a rosary showing my new design;

Fig. 2 is an enlarged vertical section of the medal in the center of Fig. 1; and

Fig. 3 is a similar section of the crucifix at the bottom of Fig. 1.

I claim:

The ornamental design for a rosary, as shown.
